(57) **CLAIM**

The ornamental design for a toy tractor, as shown and described.

DESCRIPTION

FIG. 1 is a perspective view of a toy tractor showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of another state of the toy tractor thereof.

1 Claim, 8 Drawing Sheets
